UNITED STATES PATENT OFFICE

2,451,262

ADJUSTABLE GOLF CLUB

William B. Watkins, Norfolk, Va.

Application April 4, 1945, Serial No. 586,497

2 Claims. (Cl. 273—79)

1

This invention relates to an improved golf club, and one of its objects is to provide a club with a head and means for adjusting the head to different angular relations to the shaft of the club, so that the club may be adapted for different driving strokes or plays, or adapted for use by a right or left handed person or player.

Another object of the invention is the provision of a simple and positive locking means between the head and the lower end of the shaft or handle ferrule whereby the head may be held in various adjustable positions, so that a single club may be used to do the work of many golf clubs.

Another object of the invention is to provide the blade of the head with a detachable and interchangeable weight.

With the above and other objects in view the invention consists in certain new and useful combinations, constructions, and arrangements of parts, clearly described in the following specification, and fully illustrated in the accompanying drawings, in which:

Fig. 1 is a view partly in vertical section, and partly in side elevation, showing the improved adjusting means between the handle or shaft ferrule and the blade of the head.

Fig. 2 is an end elevation, showing the index markings for adjusting the head to various striking positions.

Fig. 3 is a detail vertical sectional view, showing a detachable weight member coupled to the blade of the head.

Fig. 4 is a side elevation of a coupling pin.

Fig. 5 is a side elevation of the locking bolt.

Fig. 6 is a top plan view of the detachable weight member.

Fig. 7 is a longitudinal sectional view taken on the line 7—7 of Fig. 1, this looking in the direction of the arrows.

Referring to the accompanying drawings, which illustrate the practical application of my invention, 5 designates a handle or shaft, on the lower end of which the ferrule 6 is mounted, in any approved manner.

The ferrule 6 is constructed with an integral cylindrical extension 7, which is of smaller diameter than the sleeve or main part of ferrule which encloses the lower end of the shaft or handle. This extension 7 is formed with an internally screw threaded hole 8, which receives the upper end of the externally screw threaded shank 9 of the locking bolt 10.

The locking bolt 10 is considerably wider than the screw threaded shank 9, and is constructed

2

with parallel side faces and with parallel edge faces, while the lower end of the bolt is rounded. This enlarged body portion 11 of the locking bolt is formed with an elongated opening 12, located midway of the edges thereof, and the curved lower edge portion 12a of this opening is formed with a plurality of locking teeth 13. These teeth are disposed in concave circular relation and are of semi-conical formation adjacent opposite ends of the opening 12.

The locking bolt 10 is enclosed by the housing 14, which is provided with an axial passage 15 to receive the bolt, and to allow a certain amount of longitudinal movement of the bolt in this passage or opening. This housing is formed with a plane inner face 16, against which the inner end of the blade 17 of the head is adapted to fit.

The blade 17 is provided with a stub shaft 18, which extends from the inner end thereof, and which has a cylindrical portion 18a adjacent the inner end of the blade and another cylindrical portion 18b at the outer end of the shaft. The shaft is milled or reduced between the two portions 18a and 18b, to provide a narrower cylindrical portion 18c, and conical portions 18d and 18e outwardly thereof. The intermediate cylindrical portion 18c and the conical portions 18d and 18e are formed with locking teeth 19 which are adapted to have locking engagement with the teeth 13 of the locking bolt 10.

The cylindrical inner portion 18a of the stub shaft 18 has a snug bearing at 20 in the inner side wall 14a of the housing 14, and the outer cylindrical portion 18b has a snug bearing at 21 on the side wall 14b of the housing 14.

The locking bolt 10 is propelled in the opening or axial passage 15 of the housing 14, by turning the handle or shaft and the ferrule 6. By turning the handle and ferrule, which is positively fitted on the handle or shaft, the screw threaded shank 9 is shifted longitudinally in the extension of the ferrule. When the locking bolt is in the position shown in Fig. 1, the handle or shaft 40 is turned so that the locking bolt is forced downwardly thus disengaging the locking teeth 19 of the stub shaft 18 from the locking teeth 13 of the locking bolt. To adjust the blade or head, it is merely turned to the desired angular position, 45 and then locked by turning the ferrule 6 until the teeth 13 engage the teeth 19 on the stub shaft 18. When this is done the inner end of the blade will be forced against the inner plane face of the housing. The shaft 18 is fixed to the blade 17 so as to be rigid with it, and when the teeth 13

of the locking bolt 10 are forced into locking engagement with the teeth 19 of the stub shaft 18, the blade 17 will be rigidly locked in its adjusted position.

The housing 14 is provided with a series of index markings 22, which are located adjacent the normal position of the upper edge of the blade 17, and this blade is formed with a cooperating index mark 22a. When the blade is adjusted the angle of adjustment may be determined by the graduation markings 22.

The housing 14 is prevented from turning on the ferrule 6, by means of the latch 23, which is pivoted to the housing at 23a, and adapted to engage a recess 23b formed in the extension of the ferrule 6.

A detachable weight 25 is provided for attachment to the rear side of the blade 17, and for this purpose this weight 25 is formed with or provided with rigid dowel pins 26 and 27, located near the outer ends thereof, which are adapted to snugly engage the transverse openings 26a and 27a formed in the blade 17. The detachable weight 25 is also provided with a coupling pin or screw 28, which is constructed with a head 28a, and which is extended through the transverse and central opening 29 of the face member 25, which opening is enlarged at its outer end to receive the coil compression spring 30, which engages the screw head 28a at its outer end and the shoulder 28b at its inner end. The shank of the pin 28 is formed with a circumscribing groove 31a which is engaged by the split ring 31, and this ring normally engages the shoulder 28c of the weight 25. The inner end of the pin 28 is provided with a bayonet slot 32, which couples to a pin 32a in a passage formed in the blade 17. By tightening the pin on the blade, the spring 30 is placed under compression, thus increasing the pressure on the meeting faces of the blade 17 and the weight 25. The split ring 31 is used to assemble the pin 28 in the weight and keep it from being detached from the face member, so that it will always be in position.

It is obvious that various types of weights may be provided, and each of these coupled to the blade in the manner described, to provide a club leaving the proper balance to watch the stroke to be employed.

It is understood that various changes in the details of construction, their combination and arrangement, and in the selection and use of materials, may be made, within the scope of the invention, as defined in the claims hereof.

Having described my invention, I claim as new:

1. A golf club which includes a handle shaft, a ferrule on one end of said handle shaft, an

internally screw threaded boss projecting axially from the ferrule, a housing rotatably mounted on the boss, a bolt slidable longitudinally in said housing, said bolt having a longitudinal elongated slot extending therethrough, the housing having an opening in one side wall communicating with the slot in the bolt, a blade, a stud extending axially from one end of the blade, said stud entering the opening in the housing and extending through the slot in the bolt, peripheral teeth on the stud, teeth on one end wall of the slot for cooperation with the teeth on the stud in holding the blade against turning movement relative to the housing and a threaded shank on the bolt 10 threadedly engaged in the threaded boss whereby when the handle shaft is rotated relative to the housing the bolt will be moved to engage or disengage the teeth thereon with those of the stud.

2. A golf club which includes a handle shaft, a ferrule on one end of said handle shaft, an internally screw threaded boss projecting axially from the ferrule, a housing rotatably mounted on the boss, a bolt slidable longitudinally in said housing, said bolt having a longitudinal elongated slot extending therethrough, the housing having an opening in one side wall communicating with the slot in the bolt, a blade, a stud extending axially from one end of the blade, said stud entering the opening in the housing and extending through the slot in the bolt, peripheral teeth on the stud, teeth on one end wall of the slot for cooperation with the teeth on the stud in holding the blade against turning movement relative to the housing and a threaded shank on the bolt 20 threadedly engaged in the threaded boss whereby when the handle shaft is rotated relative to the housing the bolt will be moved to engage or disengage the teeth thereon with those of the stud.

3. A golf club which includes a handle shaft, a ferrule on one end of said handle shaft, an internally screw threaded boss projecting axially from the ferrule, a housing rotatably mounted on the boss, a bolt slidable longitudinally in said housing, said bolt having a longitudinal elongated slot extending therethrough, the housing having an opening in one side wall communicating with the slot in the bolt, a blade, a stud extending axially from one end of the blade, said stud entering the opening in the housing and extending through the slot in the bolt, peripheral teeth on the stud, teeth on one end wall of the slot for cooperation with the teeth on the stud in holding the blade against turning movement relative to the housing and a threaded shank on the bolt 25 threadedly engaged in the threaded boss whereby when the handle shaft is rotated relative to the housing the bolt will be moved to engage or disengage the teeth thereon with those of the stud.

4. A golf club which includes a handle shaft, a ferrule on one end of said handle shaft, an internally screw threaded boss projecting axially from the ferrule, a housing rotatably mounted on the boss, a bolt slidable longitudinally in said housing, said bolt having a longitudinal elongated slot extending therethrough, the housing having an opening in one side wall communicating with the slot in the bolt, a blade, a stud extending axially from one end of the blade, said stud entering the opening in the housing and extending through the slot in the bolt, peripheral teeth on the stud, teeth on one end wall of the slot for cooperation with the teeth on the stud in holding the blade against turning movement relative to the housing and a threaded shank on the bolt 30 threadedly engaged in the threaded boss whereby when the handle shaft is rotated relative to the housing the bolt will be moved to engage or disengage the teeth thereon with those of the stud.

5. A golf club which includes a handle shaft, a ferrule on one end of said handle shaft, an internally screw threaded boss projecting axially from the ferrule, a housing rotatably mounted on the boss, a bolt slidable longitudinally in said housing, said bolt having a longitudinal elongated slot extending therethrough, the housing having an opening in one side wall communicating with the slot in the bolt, a blade, a stud extending axially from one end of the blade, said stud entering the opening in the housing and extending through the slot in the bolt, peripheral teeth on the stud, teeth on one end wall of the slot for cooperation with the teeth on the stud in holding the blade against turning movement relative to the housing and a threaded shank on the bolt 35 threadedly engaged in the threaded boss whereby when the handle shaft is rotated relative to the housing the bolt will be moved to engage or disengage the teeth thereon with those of the stud.

6. A golf club which includes a handle shaft, a ferrule on one end of said handle shaft, an internally screw threaded boss projecting axially from the ferrule, a housing rotatably mounted on the boss, a bolt slidable longitudinally in said housing, said bolt having a longitudinal elongated slot extending therethrough, the housing having an opening in one side wall communicating with the slot in the bolt, a blade, a stud extending axially from one end of the blade, said stud entering the opening in the housing and extending through the slot in the bolt, peripheral teeth on the stud, teeth on one end wall of the slot for cooperation with the teeth on the stud in holding the blade against turning movement relative to the housing and a threaded shank on the bolt 40 threadedly engaged in the threaded boss whereby when the handle shaft is rotated relative to the housing the bolt will be moved to engage or disengage the teeth thereon with those of the stud.
